United States Patent

Des. 241,632

Patented Sept. 28, 1976

241,632

ISLAND CANOPY

Eliot F Noyes, New Canaan, Conn., assignor to
Mobil Oil Corporation

Filed June 10, 1974, Ser. No. 477,956

Term of patent 14 years

Int. Cl. D25—03

U.S. Cl. D25—56

FIGURE I

FIGURE II

FIG. 1 is a bottom view of the new elongated island canopy with spaced apart circular sections containing radiating panels. The top of the island canopy is plain and unornamented.

FIG. 2 is a side view of the column supported elongated island canopy of FIG. 1 showing the circular section as downwardly extending sections of the canopy and said columns provided with circular reflective light members spaced beneath said extending circular sections.

We claim:

The ornamental design for an island canopy, as shown and described.
